US00D945649S

(12) **United States Design Patent** (10) Patent No.: **US D945,649 S**
Shikhavtsov (45) Date of Patent: **** Mar. 8, 2022**

(54) **EXTERNAL THERMAL INSULATION
COMPOSITE PANEL**

(71) Applicant: **Volodymyr Shikhavtsov**, Kyiv (UA)

(72) Inventor: **Volodymyr Shikhavtsov**, Kyiv (UA)

(**) Term: **15 Years**

(21) Appl. No.: **35/510,372**

(22) Filed: **Mar. 13, 2020**

(80) **Hague Agreement Data**

Int. Filing Date: **Mar. 13, 2020**

Int. Reg. No.: **DM/208533**

Int. Reg. Date: **Mar. 13, 2020**

Int. Reg. Pub. Date: **Sep. 18, 2020**

Primary Examiner — Richard Kearney

(57) **CLAIM**

The ornamental design for external thermal insulation composite panel, as shown and described.

DESCRIPTION

1. External thermal insulation composite panel

1.1 : Top-left perspective view

1.2 : Bottom-right perspective view

1.3 : Top

1.4 : Right

1.5 : Back

1.6 : Front

1.7 : Left

The marble chips pattern is a symbolic marking of the decorative and protective natural/artificial stone-based coating and does not form part of the claimed design; the insulation material pattern is symbolic and does not form part of the claimed design; reproduction.

1 Claim, 7 Drawing Sheets
